UNITED STATES PATENT OFFICE.

HARRIETT C. BRYANT, OF NEW MILFORD, CONNECTICUT.

DESIGN FOR WALL PAPER.

Application filed May 2, 1924. Serial No. 9,465. Term of patent 7 years.

To all whom it may concern:

Be it known that I, HARRIETT C. BRYANT, a citizen of the United States, residing in New Milford, Litchfield County, Connecticut, have invented a new, original, and ornamental Design for Wall Paper; of which the following is a specification, reference being had to the accompanying drawing, showing a representative fragment of the paper.

I claim:

The ornamental design for wall paper, as shown.

HARRIETT C. BRYANT.
